UNITED STATES PATENT OFFICE.

MICHAEL WOJTECKI, OF CHICAGO, ILLINOIS.

DESIGN FOR A BADGE.

No. 39,307.

Specification for Design.

Patented May 19, 1908.

Application filed March 20, 1908. Serial No. 422,374. Term of patent 7 years.

To all whom it may concern:

Be it known that I, MICHAEL WOJTECKI, a citizen of the United States, residing at the city of Chicago, in the county of Cook and State of Illinois, have invented a new, original, and ornamental Design for a Badge, of which the following is a specification, reference being had to the accompanying drawing, forming part thereof.

The figure is a plan of the badge, showing my new design.

I claim:

The ornamental design for a badge as shown.

MICHAEL WOJTECKI.
